UNITED STATES PATENT OFFICE.

WILLIAM H. FRANCIS, OF WASHINGTON, DISTRICT OF COLUMBIA.

GALLEY-LOCK.

1,210,923.

Specification of Letters Patent. Patented Jan. 2, 1917.

Application filed January 26, 1916. Serial No. 74,406.

To all whom it may concern:

Be it known that I, WILLIAM H. FRANCIS, a citizen of the United States, residing at Washington, in the District of Columbia, have invented a new and useful Galley-
5 Lock, of which the following is a specification.

The present invention appertains to galley locks for printers' galleys, and it is the
10 object of the invention to provide a type or
slug holding member assembled with the
galley in a novel and improved manner,
whereby the slugs or lines of type can be
effectively held in place in the galley, the
15 holding member being adjustable and mov-
able out of the way without completely de-
taching it from the galley.

It is also within the scope of the invention
20 to provide a galley lock which is ex-
tremely simple, non-encumbering and inex-
pensive in construction, and which will serve
its office in a thoroughly practical, reliable
and efficient manner.

With the foregoing and other objects in
25 view which will appear as the description
proceeds, the invention resides in the com-
bination and arrangement of parts and in
the details of construction hereinafter de-
scribed and claimed, it being understood
30 that changes in the precise embodiment of
the invention herein disclosed can be made
within the scope of what is claimed without
departing from the spirit of the invention.

The invention is illustrated in the accom-
35 panying drawing, wherein:

Figure 1 is a plan view of a printer's galley
incorporating the present improvements.
Fig. 2 is a cross section taken on the line
2-2 of Fig. 1. Fig. 3 is a sectional detail
40 illustrating the holding member swung up-
wardly out of the way.

In the drawing, there is depicted a printer's galley 1, one side wall 2 of which is provided with a longitudinal upstruck corrugation or rib forming a longitudinal inner groove 3. Supported adjacent and parallel with the other side wall 4 of the galley is a resilient rod 5 having its terminals engaged with the ends of the galley. The
45 slugs or lines of type are placed within the galley in the usual manner, and are disposed between the rod 5 and opposite side wall 2.

The slugs or lines of type are held snugly
50 in place by a holding member 6 disposed
transversely within the galley, and composed
of a plate or bar of sheet metal. The mem-

ber 6 is provided adjacent one end with an aperture 7 through which the rod 5 extends, and the other end of the member 6 is provided with a rounded lug 8 fitting within the groove 3 to assist the rod 5 in guiding the member 6 for longitudinal adjustment within the galley to accommodate the slugs. That end of the member 6 engaging the rod 5 is provided with an angularly extending spring tongue 9 between the rod 5 and side wall 4 of the galley and projecting toward that end of the galley adjacent which the slugs are disposed. The tongue 9 is arranged at less than a right angle with the member 6 and its free end bears against the rod 5, thereby tending to swing the member 6 toward the slugs. The aperture 7 is such that the member 6 binds upon the rod 5 when the member 6 is swung at right angles with said rod, due to the tension of the tongue 9, but when the member 6 is swung out of right angled position with the rod 5, it can be slid longitudinally. When the member 6 is moved against the slugs, it assumes a right angled position with the rod 5 and side walls of the galley, to hold the slugs in place properly, and at the same time, the member 6 binds upon the rod 5, to prevent it from moving away from the slugs. The member 6 is held in this position by the spring tongue 9.

The holding member 6 can be swung out of the way readily, this being accomplished by springing the wall 2 outwardly so that the lug 8 can move out of the groove 3, and which will permit the member 6 to be swung upwardly out of the way, as illustrated in Fig. 3, to seat on the wall 4.

The advantages gained by the present im-
provements will suggest themselves to those
skilled or versed in the art, without fur-
ther comment being necessary.

In some cases, both ends of the galley are
open, and two reversed holding members can
be used to hold the slugs therebetween.

Although a special form of galley is illus-
trated and described, it will be apparent that
the invention can be used upon various forms
of galleys.

Having thus described the invention, what
is claimed as new is:

1. The combination with a printer's gal-
ley, of a transverse type holding member
having one end mounted adjacent one wall
of the galley for longitudinal adjustment,
said member being swingable upwardly out

of the way, and the opposite side wall of the galley and free end of said member having interengageable means for holding said member in operative position and for longitudinal adjustment.

2. The combination with a printer's galley, of a longitudinal rod carried thereby adjacent one side wall, and a type holding member slidably engaging said rod for longitudinal adjustment, and adapted to be swung thereon into and out of type holding position.

3. The combination with a printer's galley, of a longitudinal rod carried thereby adjacent one side wall, a transverse type holding member having one end slidable upon said rod, said member being swingable upwardly out of the way, the opposite

side wall of the galley having a longitudinal groove, and the free end of said member having a lug engageable in said groove.

4. The combination with a printer's galley, of a longitudinal rod carried thereby, and a type holding member slidably engaging said rod for longitudinal adjustment and adapted to be swung thereon into and out of type holding position, said member having a spring tongue bearing against the rod to move said member to type holding position.

In testimony that I claim the foregoing as my own, I have hereto affixed my signature in the presence of two witnesses.

WILLIAM H. FRANCIS.
